[57] **CLAIM**

The ornamental design for a combined calendar and photograph holder, as shown and described.

DESCRIPTION

FIG. 1 is a perspective view of the combined calendar and photograph holder showing my new design, with the broken line showing for illustrative purposes only and forming no part of the claimed design;

FIG. 2 is a front elevational view thereof;

FIG. 3 is a right side elevational view, the left side elevational view being a mirror image thereof;

FIG. 4 is a rear elevational view thereof;

FIG. 5 is a top plan view thereof; and,

FIG. 6 is a bottom plan view thereof.

FIG. -2

FIG. -1

FIG. - 6

FIG. - 5
